PROCESS OF OBTAINING NITRO COMPOUNDS.

1,309,577.

Specification of Letters Patent.

Patented July 8, 1919.

Application filed May 11, 1915. Serial No. 27,301.

To all whom it may concern:

Be it known that I, FLETCHER B. HOLMES, of Woodbury, in the county of Gloucester, and in the State of New Jersey, have invented a certain new and useful Improvement in Processes of Obtaining Nitro Compounds, and do hereby declare that the following is a full, clear, and exact description thereof.

10 My invention relates particularly to a process for obtaining nitro-compounds from liquids containing a large percentage of non-nitrifiable constituents, as for example, petroleum products.

15 Petroleum products both as they occur naturally and after various treatments to which they are subjected in their refining, contain nitrifiable hydrocarbons in differing amounts, while the main body of the petroleum products is usually incapable of nitration with nitric acid or mixtures of nitric and sulfuric acids to form useful nitro-compounds. The nitrifiable constituents in the petroleum products may be aromatic hydrocarbons, such as benzol, toluol, xylol, etc. The nitrifiable constituents may be acted upon to form mono-, di- or possibly tri-nitro-compounds or mixtures of the same, and nitro-compounds thus formed may be

20 separated from the remaining constituents in the petroleum products. Where this is done in the usual way, however, that is to say, by mixing the petroleum products and the acids in a nitrating vessel in the usual way, the relatively larger volume of non-nitrifiable petroleum products results in a low capacity of the nitrating unit in output of nitro compounds.

25 The object of my invention is to provide a process for obtaining the nitro-compounds in question in an effective manner by the rapid nitration of the constituents of the petroleum products which are capable of being acted upon by the nitrating acids.

30 I have discovered that the nitration can be effectively accomplished by forcing the petroleum products into a vessel at the bottom thereof which contains a mixture of the nitric and sulfuric acids. In this way the petroleum products will pass upwardly through the body of acids and during the passage of the same through the acids may or may not be agitated as desired. The petroleum products because of their low den-

sity rise rapidly through the acids, and the height of the container for the acids may be made sufficiently great to accomplish the nitration of the nitrifiable constituents in a very effective manner. The nitro products thus formed accumulate partly on the surface of the acids where they are dissolved in or in contact with the unnitrated petroleum products while a portion of the nitro-compounds also remains with the body of the acids. The separate layer of nitro-compounds and petroleum products on the top of the body of acids may be drawn off continuously and the unnitrated petroleum products separated from the nitro-compounds by distillation. The layer of acids containing the remainder of the nitro-compounds may then be allowed to stand so as to separate the nitro-compounds from the spent acid. The upper layer which comprises the nitro-compounds is drawn off, washed, neutralized and dried in the usual way. The process is preferably conducted with the use of a condenser so as to prevent the escape of gasolene vapors during the process. In carrying out my invention furthermore, I find it advantageous to feed the acids in at the top of the nitrating vessel at a uniform rate and to draw off the same at the bottom thereof at the same rate, the conditions being so controlled as to substantially prevent the acids leaving the bottom of the vessel from carrying with them any unnitrated petroleum products. The acids discharged from the vessel do, however, carry out some of the nitro-compounds. When operating in this manner it is preferable also to feed in the petroleum products continuously near the bottom of the nitrating vessel, and draw off the same with a quantity of the nitro-compounds at the top of the vessel.

35 While my invention is capable of embodiment in many different forms, for the purpose of illustration I have described only one form of my invention herein, and have shown only one form of apparatus for use in connection with my process in the accompanying drawings, in which—

40 The figure represents diagrammatically an apparatus with which my invention is capable of being carried out.

45 In the drawings I have shown a nitrating vessel 1, having a valved inlet pipe 2, near

the top thereof for mixed acids supplied to the nitrating vessel from an acid tank 3. This acid tank 3 is adapted to receive its supply of mixed nitric and sulfuric acids 5 by means of a pipe 4 leading from a pump 5, of any suitable construction. This pump 5 receives its acids from a valved pipe 6 which leads from an acid and nitro-compound separating tank 7 and which is provided with a valved draw-off pipe 8. The mixed acids which are fed into the nitrating vessel 1, pass downwardly in a continuous stream through the same and after coming into contact with the hydrocarbons therein 10 are discharged through a valved pipe 9 into the separating tank 7. While the downward current of heavy mixed acids is thus produced in the nitrating chamber 1, an oppositely, that is to say upwardly, moving current 15 of the hydrocarbons is produced therein by forcing gasolene from a tank 10 provided with air pressure, through a valved pipe 11 and a spraying nozzle 12 connected to said pipe 11 located in the lower part of 20 the nitrating vessel 1. The gasolene which passes upwardly through the body of acids in the nitrating vessel 1, passes over cooling pipes 12^a and accumulates in a layer 13 over the top of the acids in the nitrating chamber 25 1, together with a quantity of the nitro-compounds dissolved in or in contact with the body of hydrocarbons in said layer 13. The mixed hydrocarbons and nitro-compounds are drawn off from this layer 13 by a 30 pipe 14 to a condenser 15, which condenses any volatilized hydrocarbons. The mixed gasolene and nitro-compounds pass out of the condenser 15 into one of the tanks 16 and 17 by means of the valved pipes 18 and 19 35 communicating therewith, where they are washed with a dilute alkaline solution to neutralize any acid remaining therein, and then with water to free the same from alkali. The waste water from the tank 16 and 17 is 40 discharged through a valved pipe 20 which communicates with discharge pipes 21 and 22 located on the tanks 16 and 17 respectively. The gasolene and nitro-compounds are thereafter run into a still 23 by means of 45 valved pipes 24 and 25 from the tanks 16 and 17. The liquids thus introduced into the still 23 are separated by the application of heat in any desired manner, preferably while subjected to a current of steam or inert 50 gas from a pipe 26 located in the bottom of the still, thus distilling off the unnnitrated gasolene through a pipe 27 which passes into a condenser 28 and thence into a gasolene storage tank 29. Preferably a reduced pressure 55 is maintained in the still 23 by means of a pump 29^a connected by a pipe 30 to the discharge end of the condensing coil 28. The nitro-compounds thus remaining in the still 23, are drawn off from the same by 60 means of a valved pipe 31, through which

they pass into a tank 32 having a valved draw-off pipe 33. As the acids drawn off from the nitrating vessel 1, and which accumulate in the tank 7, also contain a percentage of the nitro-compounds, the acids in 70 the tank 7 are allowed to stand until the nitro-compounds therein accumulate in a layer 34 at the top of the tank 7, from which they are drawn off by means of a valved pipe 35 into the tank 32. In this way the 75 nitro-compounds formed in the process, and which become dissolved in or which remain in contact with the nitrating acids and the unnnitrated hydrocarbons, become collected at the same point. The nitro-hydrocarbons 80 which thus accumulate in the tank 32 may be neutralized and washed in the usual way.

Although I have described the use of a mixture of sulfuric and nitric acids for removing the nitrifiable constituents from 85 petroleum products it should be understood that nitric acid alone can also be used under certain conditions though ordinarily the use of a mixture of nitric and sulfuric acids gives more satisfactory results.

While I have described my invention above in detail, I wish it to be understood that many changes may be made therein without departing from the spirit of my invention.

I claim:

1. The process which comprises forming a nitro-compound by passing a hydrocarbon liquid containing nitrifiable and a relatively large proportion of non-nitrifiable 100 constituent upwardly through a nitrating acid.

2. The process which comprises forming a nitro-compound by passing a petroleum product containing a small amount of a 105 nitrifiable aromatic constituent and a non-nitrifiable constituent upwardly through a nitrating acid, drawing off the petroleum product from above the surface of the acid and recovering the nitro-compounds formed. 110

3. The process which comprises forming a nitro-compound by passing a petroleum product containing a nitrifiable constituent upwardly through a downwardly moving current of a nitrating acid.

4. The process which comprises forming a nitro-compound by passing a petroleum product containing a nitrifiable constituent upwardly through a downwardly moving current of a nitrating acid, drawing off the 120 petroleum product from above the surface of the acid and recovering the nitro-compounds formed.

5. The process which comprises forming a nitro-compound by passing a petroleum 125 product containing a small amount of a nitrifiable aromatic constituent and a non-nitrifiable constituent upwardly through a nitrating acid, drawing off the petroleum product from above the surface of the acid 130

- and the acid from a point below the petroleum product and recovering the nitro-compounds formed.
6. The process which comprises forming a nitro-compound by passing a petroleum product containing a nitrifiable constituent upwardly through a downwardly moving current of a nitrating acid, drawing off the petroleum product from above the surface of the acid and the acid from a point below the petroleum product and recovering the nitro-compounds formed.
7. The process which comprises forming a nitro-compound by passing a petroleum product containing nitrifiable and non-nitrifiable constituents upwardly through a nitrating acid, drawing off the petroleum product from above the surface of the acid and recovering the nitro-compounds formed by distillation.
8. The process which comprises forming a nitro-compound by passing a petroleum product containing a nitrifiable constituent upwardly through a downwardly moving current of a nitrating acid, drawing off the petroleum product from above the surface of the acid and recovering the nitro-compounds formed by distillation.
9. The process which comprises forming a nitro-compound by passing a petroleum product containing a nitrifiable constituent and a relatively large proportion of a non-nitrifiable constituent upwardly through a nitrating acid, drawing off the petroleum product from above the surface of the acid and the acid from a point below the petroleum product and recovering the nitro-compounds formed by distillation.
10. The process which comprises forming a nitro-compound by passing a petroleum product containing a nitrifiable constituent upwardly through a downwardly moving current of a nitrating acid, drawing off the petroleum product from above the surface of the acid and the acid from a point below the petroleum product and recovering the nitro-compounds formed by distillation.
11. The process which comprises forming a nitro-compound by passing a petroleum product containing a nitrifiable constituent upwardly through a nitrating acid, drawing off the petroleum product from above the surface of the acid and the acids from a point below the petroleum product and recovering the nitro-compounds formed by 55 distillation of the nitro-compounds from the unnitrated constituents of the petroleum product associated therewith and separation by gravity of the nitro-compounds from the acids associated therewith.
12. The process which comprises forming a nitro-compound by passing a petroleum product containing a nitrifiable constituent upwardly through a downwardly moving current of a nitrating acid, drawing off the petroleum product from above the surface of the acid and the acid from a point below the petroleum product and recovering the nitro-compounds formed by distillation of the nitro-compounds from the unnitrated constituents of the petroleum product associated therewith and separation by gravity of the nitro-compounds from the acids associated therewith.
13. The process which comprises forming a nitro-compound by passing a petroleum product containing a nitrifiable constituent upwardly through a nitrating acid, drawing off the petroleum product from above the surface of the acid and recovering the nitro-compounds formed by distillation with the injection of steam.
14. The process which comprises forming a nitro-compound by passing a petroleum product containing a nitrifiable constituent upwardly through a downwardly moving current of a nitrating acid, drawing off the petroleum product from above the surface of the acid and recovering the nitro-compounds formed by distillation with the injection of steam.
15. The process which comprises forming a nitro-compound by passing a petroleum product containing a nitrifiable constituent upwardly through a nitrating acid, drawing off the petroleum product from above the surface of the acid, while subjecting the same to condensation and recovering the nitro-compounds formed.

In testimony that I claim the foregoing I have hereunto set my hand.
